UNITED STATES PATENT OFFICE

98,382

DESIGN FOR A BOTTLE

Ferdinand S. Barbiers, Lancaster, Ohio, assignor to General Glass Corporation, Lancaster, Ohio, a corporation of Ohio

Application December 3, 1935, Serial No. 59,883

Term of patent 14 years

To all whom it may concern:

Be it known that I, Ferdinand S. Barbiers, a subject of the King of Belgium, residing at Lancaster, in the county of Fairfield and State of Ohio, have invented a new, original, and ornamental Design for Bottles, of which the following is a specification, reference being had to the accompanying drawing, forming part thereof.

Fig. 2 is a half section on the line II—II Fig. 1, looking to the right.

Fig. 3 is an edge view of the bottle in upright position.

Fig. 4 is a top plan view of the bottle as shown in Fig. 3.

The design applied to the face of the bottle opposite that shown in Fig. 1 is a duplicate of that shown in said Fig. 1.

I claim—

The ornamental design for a bottle substantially as shown and described.

FERDINAND S. BARBIERS.
